OSKAR SEITZ, OF BADEN, SWITZERLAND, ASSIGNOR TO AKTIENGESELLSCHAFT BROWN, BOVERI & CIE., OF BADEN, SWITZERLAND, A JOINT-STOCK COMPANY OF SWITZERLAND

ELECTRIC CURRENT RECTIFIER

Application filed September 11, 1930, Serial No. 481,116, and in Switzerland August 1, 1929.

This invention relates to improvements in electric current rectifiers of the metallic vapor type and particularly to an improved construction of such rectifiers which will 5 decrease the amount of metallic vapor continually present in the structure.

It is well-known that increased quantities of metallic vapor and, therefore, increased vapor density decreases the safety of operation of an electric current rectifier of the metallic vapor type due to the fact that the condensing capacity of the water-cooled walls of the rectifier is overtaxed. Globules of the metallic vapor are therefore likely to form 15 on the anode or anode sleeves thereby providing a so-called cathode spot which permits flow of current from the anode operating at the moment to such cathode spot rather than to the cathode proper. Such action, 20 known as backfiring, is detrimental not only to the rectifier structure itself but may cause dangerous disturbances in the alternating current supply system.

It is, therefore, among the objects of the 25 present invention to provide an electric current rectifier construction in which a cooling member is arranged interiorly of the rectifier tank to extend upwardly from the bottom thereof.

Another object of the invention is to provide a rectifier in which the anodes are arranged in a circle about a cooling member extending upwardly in the rectifier tank from the bottom thereof.

Another object of the invention is to provide an electric current rectifier in which the anodes are arranged in a circle and the cathode is in the form of an annulus arranged 40 about a cooling member extending upwardly from the bottom of the rectifier tank and interiorly thereof.

Objects and advantages, other than those above set forth, will be apparent from the 45 following description when read in connection with the accompanying drawing in which

Figure 1 is a vertical cross-sectional view through a rectifier embodying the present invention, and

Fig. 2 is a top plan view of the cooling

member formed according to the present invention.

Referring more particularly to the drawing by characters of reference, the reference numeral 3 designates a tank which is double-walled to provide a path for the circulation of a cooling medium therethrough and is arranged to contain the devices, to be described hereinafter, maintaining an electric arc through a medium, such as vaporized mercury, having a valve action on electric current. The open top of the tank 3 is closed by a cover plate 4 having a plurality of anodes 6 extending therethrough in insulated relation therewith and an upward extension 65 7 therefrom which extension is also made double-walled to permit the circulation of a cooling medium therethrough and is herein-after called the condensing dome. The bottom of the tank is formed in the shape of a 70 hollow truncated cone having its apex end extending downwardly and the aperture therethrough is closed by an annular closure plate 8 having an annular channel formed therein to receive an electric current conductive vaporizable material 9 having a valve action, when vaporized, on an electric current, which material serves as the cathode. The anodes 6 are surrounded by sleeves 11 depend- 75 ing from the insulator toward the bottom of the tank 3 and the closure plate 8 is connected with the tank by suitable non-conductive means 12 sealing the joint between the tank and the closure plate.

A substantially cylindrical, double-walled cooling member 13 having walls in the shape of a star is mounted on the closure plate 8 and is sealed thereon by suitable sealing means 14 in such manner as to close the aperture through the closure plate 8. The member 13 extends upwardly from the closure plate 8 as a cooling member, reentrant with respect to the casing 3, and beyond the open bottom ends of the anode sleeves 11 substantially into the plane of the anodes 6 and adjacent the bottom of the cooling dome 7. The cooling member is connected with and made a part of the path for the cooling medium circulating through the tank wall by 80 90 95 the pipes 16 and 17. The interior of the 100

cooling member 13 is furthermore in contact with the atmosphere and the star-shaped walls thereof form cooling paths for mercury vaporized from the cathode 9 which vapor may flow upwardly in its natural paths from the cathode and the condensed mercury may return to the cathode without coming into contact with the arc flowing between an anode 6 and the cathode 9. The walls of the cooling member 13 may be made in any other desirable form so long as sufficient cooling area is presented thereby.

It will be seen that the present invention provides a rectifier construction in which the quantity of vapor produced by the heating action of the arc from the cathode is materially diminished by condensation thereof in the immediate vicinity of the cathode and that the vapor so condensed may return to the cathode without again coming into contact with the electric arc. The upper end of the cooling member extending beyond the open ends of the anode sleeves tends particularly to reduce the vapor density about the ends of the sleeves. The vapor in the space between the lower end of the condensing dome 7 and the cooling member 13 is subject to the cooling of both the dome and the cooling member which tends to create a partial vacuum therein whereby the vapor rising from the cathode is drawn away from the open ends of the anode sleeves. The total result of all of the above effects is to decrease the vapor density in the anode sleeves thereby preventing condensation of the vapor on the anodes or sleeves and eliminating cathode spots which cause backfiring.

Although but one embodiment of the present invention has been illustrated and described, it will be apparent to those skilled in the art that various changes and modifications may be made therein without departing from the spirit of the invention or from the scope of the appended claims.

The invention claimed is:

1. In an electric current rectifier of the metallic vapor type, a double-walled tank having an aperture through the bottom thereof, a plurality of anodes extending into said tank through the cover plate thereof, an annular plate having an annular channel therein to receive cathode material, said plate partially closing the aperture through the bottom of said tank, and a hollow cooling member arranged to close the aperture in said plate and extending upwardly interiorly of said tank into substantially the plane of said anodes, the interior surface of said cooling member being in contact with the atmosphere.
2. In an electric current rectifier of the metallic vapor type, a double-walled tank having an aperture through the bottom thereof, a plurality of anodes extending into said tank through the cover plate thereof, an annular plate having an annular channel

therein to receive cathode material, said plate partially closing the aperture through the bottom of said tank, and a hollow double-walled cooling member arranged to close the aperture in said plate and extending upwardly interiorly of said tank into substantially the plane determined by the ends of said anodes, said tank and said cooling member forming a path for the circulating of a cooling medium therethrough.

3. In an electric current rectifier, a casing, a circle of spaced anodes depending into said casing, an annular cathode of diameter less than the diameter of the circle formed by said anodes supported within said casing adjacent the bottom thereof, and a cooling member of cylindrical contour and diameter less than the diameter of said cathode reentrant through the bottom of said casing to a point substantially at the level of the said circle of anodes, the interior surfaces of said cooling member being open to the atmosphere.

In testimony whereof I have hereunto subscribed my name this 28th day of August, A. D. 1930.

OSKAR SEITZ.
